TELEVISION SYSTEM

John Logie Baird, London, England, assignor of
one-half to Television Limited, London, Eng-
land, a British company

Application January 6, 1928, Serial No. 244,963,
and in Great Britain January 26, 1927

10 Claims. (Cl. 178—5)

This invention relates to the transmission of signals for television and like purposes, and has for its object to provide an improved method of and apparatus for such transmission.

5 It is advantageous from the point of view of speed of transmission that a picture or view should be explored in a number of different sections simultaneously, but heretofore the transmission of the signals arising from such simultaneous explorations has necessitated a corresponding number of lines in the case of wired transmission, or of separate wave-lengths for 10 wireless transmission.

This invention accordingly comprises in a television system, the method of transmitting a plurality of individual signals consisting in recording them simultaneously or in concurrent groups on a record-element or elements and thereafter reading all the individual records in succession 20 (for example, at a higher speed) by a device which is operatively connected to the transmitter.

According to another feature of this invention, the reading device may have associated with 25 it means for wiping out the record which has just been read, so that a fresh record may be made immediately thereafter.

According to another feature of this invention it consists in exploring simultaneously various 30 sections of a picture or view to be transmitted, recording the groups of signals corresponding to each section of the picture on a record element and traversing the record thus formed by a device which reads the record and transmits 35 the signals to the receiving station.

A similar but reversed arrangement may be used at the receiving station, the signals being transmitted successively at, say, a high rate, and recorded on an element or group of elements, 40 such signals being thereafter read simultaneously in groups on different parts of the record.

This invention also covers certain details of the apparatus as hereinafter described.

In the accompanying drawing—

45 Figure 1 is a diagrammatic representation of one form of apparatus suitable for carrying out the present invention;

Figures 2 and 3 are diagrammatic representations of alternative forms of apparatus.

50 Referring first to Figure 1, which illustrates diagrammatically a construction of apparatus in which magnetic recording is used, there is provided a series of discs 40, 41, 42 of steel or other suitable magnetic material mounted on 55 a shaft 43 which is arranged to be rotated at

any suitable speed. The number of discs is equal to the number of sections in which the picture is explored, and one disc is appropriated to each section.

It will be understood that any suitable means 60 adapted to explore several sections of an image simultaneously may be used for the purpose. For instance, a plurality of separate exploring devices may be used, each positioned so as to scan one section only of the image. If preferred, 65 an exploring device such as is shown in my co-pending application Serial No. 244,964, filed Jan. 6, 1928, in which a single rotating disc is capable of simultaneously exploring different sections of an image, may be utilized.

The signals derived from the light-sensitive or photoelectric cell for each section are applied 70 respectively to magnetizing coils 44, 45, 46, so as to make a corresponding record on each of the discs during its rotation. Each of the discs also 75 has associated with it a search-coil, indicated at 47, 48 and 49, this coil being so mounted that it can be rotated in the opposite direction to the disc at a higher speed. Conveniently, when three discs are used, the search-coil will rotate at twice 80 the speed of the disc.

Each search-coil has associated with it a wiping-out-coil energized by alternating current of 85 a suitable frequency, and this coil is rotated immediately behind the search-coil so that after a record has been read it is erased, and the record-element is left ready to receive a new record; these wiping-out-coils are indicated at 50, 51, 52.

In the operation of this device, the records for 90 the three sections of the picture being transmitted are made concurrently and impressed upon the respective discs as record-elements. When the record on the first disc has been completed, as indicated diagrammatically by the line 53, the search-coil 47 is connected in circuit so that on its 95 next revolution from the position indicated in Figure 1 it reads this record, and simultaneously erases it. Since this coil is rotating at twice the speed of the disc, it completes the reading during one-third of a revolution of the disc, and is thereupon disconnected, and the search-coil 48 is connected in the transmitting circuit in its place. It then reads and transmits the record on the disc 41, and on the completion thereof is disconnected, and the search-coil 49 reads and transmits the record on the disc 42.

The record on the disc 40 was erased immediately after it was read, and the coil 44 impressed 100 a new record thereon, the recording commencing immediately after the reading of the previous rec- 110

ord commenced and continuing whilst all three records on the discs 40, 41, 20 are being read and transmitted. Since the search-coils rotate at twice the speed of the discs, the disc 40 will have 5 had a full record impressed upon it by the time the search-coil 49 has finished reading the disc 42 so that the cycle of operations of reading the three discs in succession can be repeated. In this way, therefore, the magnetizing coils are in 10 operation practically continuously, and each search-coil is reading and transmitting a record for one revolution in three, so that the whole process of recording, reading and transmitting is a substantially continuous one, and the rate 15 of transmission of the set of signals constituting the complete picture (made up of the three sections) is three-times as great as it would be with a single exploring and transmitting device.

In order to obtain a cyclic series of operations, 20 it will be seen that each search-coil in its rotation should meet the head end of the record it is to read at an appropriate time, and the simultaneous records on the three discs, should therefore be started 120° apart. This is most readily effected by selection of the position of the exploring disc for each section.

Other arrangements of recording element may be used, such for example as is illustrated in Figure 2. In this case there is a single disc 10 of 30 steel or other suitable magnetic material mounted on a shaft 11 which is arranged to be rotated at any suitable speed. The picture may be explored in three sections, and the exploring devices are connected respectively to three magnetizing-coils 35 12, 13, 14, which are spaced apart around the periphery of the disc 10. In the particular arrangement illustrated, these coils are spaced 60 degrees apart around one-half of the disc. The disc is rotated at such a speed that the exploration of each section (and therefore the exploration of the whole area) takes place whilst the disc is rotating through an angle of 60° .

For convenience in description a particular radius 15 of the disc will be taken as a reference 45 member, this radius being one through the magnetizing-coil 12 at the instant that the exploration commences. As this radius moves in a clockwise direction, the individual signals received by each of the coils 12, 13, 14 will magnetize the disc as it passes under them, thereby 50 producing a record indicated by the line 16. When the radius 15 has advanced through an angle of 60° to the position indicated at 17, the record formed by the coil 12 will have reached as 55 far as the beginning of the record formed by the coil 13, and similarly for the other two coils, so that a continuous record extending over one-half of the circumference of the disc will have been formed, such record having been formed during 60 the time occupied by one-sixth of a revolution of the disc.

The reading of this record and its transmission to the receiving-station is effected by means of a reading-coil or search-coil 18 which is situated 65 at any convenient position, for example, near the coil 12, so that as the record is formed it passes under it. In the arrangement indicated, the reading of the record 16 commences when the reference-radius 15 reaches the position 19, and 70 continues whilst the disc is completing a half-revolution, that is to say, until the reference-radius 15 reaches the position 20. The magnetization of the disc in accordance with the various signals received from the exploring devices induces electrical impulses in the coil 18 which are 75

amplified by any suitable device 21 and transmitted for example by an aerial 22 to the receiving station.

A demagnetizing coil 23 supplied with alternating current at any suitable frequency, is preferably provided immediately behind the search-coil 18 so as to wipe out the record as soon as it has been read and transmitted, thereby leaving the disc ready to receive another record.

It will be appreciated that as soon as the tail-end 24 of the record 16 has passed the coil 12, a second exploration and recording of the signals derived therefrom may be commenced, such record being formed on that half of the disc 10 which was idle during the operation already described, and this sequence of operations may be repeated indefinitely.

In the modified construction illustrated in Figure 3, a rotatable magnetic disc 25 is used, and there are mounted adjacent to it a plurality of magnetizing coils 26, 27, 28, 29, four spaced apart 90° being illustrated. Each of these coils is energized through a selenium cell or other light-sensitive body which is used in conjunction with an exploring device for exploring a section of the view or scene to be transmitted. In this case, the view is divided into four sections.

A reading-coil or search-coil 30 is so mounted that it can be rotated relatively to the disc, and in the example illustrated it is rotated in the opposite direction to the disc, and at a higher speed, say four times that of the disc. The search-coil 30 may also carry with it a wiping-out coil 31 in the manner previously described.

Taking a particular radius 32 for reference purposes, the mode of operation of this apparatus will be as follows. When the radius 32 is in the position indicated, the making of the record commences, and it continues whilst the disc turns through a quarter-revolution, that is to say, until the radius 32 occupies the position 33. At this point the record will be complete, extending entirely around the circumference of the disc, and the whole of the view or picture will be recorded thereon. The search-coil 30 is rotated in the direction indicated at a high speed, so as to read and transmit the record, and the speed is conveniently such that the search-coil makes one complete revolution during the time in which the radius 32 turns from the position 33 to the position 34. That is to say, the time occupied in the transmission is somewhat less than the time occupied in the recording of the signals, the difference being due to the fact that the disc 25 is rotating in one direction whilst the search-coil 30 is rotated in the other direction. A complete cycle of operations has thus been concluded, and may be repeated, recording taking place during the next quarter-revolution of the disc and transmission during the last quarter.

With this apparatus the rate at which the signals are read and transmitted is somewhat greater than four times the rate at which they are recorded, and the light-sensitive cells are operative during only about one-half of the total time. The rate of transmission of the signals is thereby greater than could be employed using a single light-sensitive cell to explore the whole picture or view which is to be transmitted.

It will be appreciated that the search-coil is required to be operative only during alternate revolutions, and this may be arranged in any convenient fashion. As diagrammatically indicated, this coil may be coupled to the output amplifier through two rotary switches 35, 36 which are

provided over a part of their circumference with a contact-strip, and which rotates in the same direction as the coil 30 but at a slower rate. Each contact-strip bridges a contact from the coil 30 and a contact to the output amplifier and by suitably selecting the relative rates of movement of the coil 30 and the switches, and the length of the contact-strips, the coil 30 is isolated during each alternative revolution.

10 A similar arrangement may be used for coupling the coils 26, 27, 28 and 29, to their respective light-sensitive cells, the rotary switches being indicated by the character 37.

Obviously, however, the inoperative periods 15 of these last-mentioned coils may be obtained by adjustment of the exploring devices.

At the receiving station the signals may be used directly to control the variable light source which is ordinarily used in a television receiving-station, or apparatus similar to that above described may be used in the reverse manner, that is to say, a record is impressed upon it at a high speed, and this record is subsequently read in concurrent sections by various devices, each of which 25 controls its own source of light or equivalent device.

Whilst it is not intended that the records should ordinarily be other than transient, it will be appreciated that permanent records of a view 30 or picture may be made in accordance with this invention, so that they can be transmitted and viewed, or reproduced at the receiving-station and viewed at any subsequent time.

Finally, it is to be understood that the invention 35 is not limited to the particular magnetic recording device hereinbefore described, for various other methods of recording electrical impulses are available and any such may be used in the manner hereinbefore set forth.

40 I claim:—

1. A method for the transmission of images consisting in exploring simultaneously individual luminous points in different portions of an image, recording simultaneously the explored individual 45 luminous points in the different portions of the image, sending successively the recorded portions of the image, and reproducing simultaneously the individual luminous points in different portions of the image thus sent.

50 2. The method of television transmission which comprises scanning simultaneously individual points in a plurality of different portions of an image, recording the light variations from each portion separately, transmitting the separate 55 recordings in succession, and reproducing simultaneously individual points in the separate transmitted recordings.

60 3. The method of television transmission which comprises scanning simultaneously a plurality of different portions of an image, transforming the light variations of each portion into electrical variations, recording the electrical variations for each portion separately, transmitting the separate recordings in succession, and 65 reproducing simultaneously individual points in the separate transmitted recordings.

70 4. The method of television transmission which comprises scanning simultaneously a plurality of different portions of an image, transforming the light variations from each portion into electrical variations, recording magnetically the electrical variations from each portion separately, transmitting the separate recordings in

succession, and reproducing simultaneously individual points in the separate simultaneous recordings.

5. The method of transmitting television signals which comprises simultaneously scanning a plurality of different sections of an image, recording magnetically the light variations from each section separately, transmitting the recording from each image separately, and erasing each recording after each transmission.

6. The method of transmitting television signals which comprises simultaneously scanning a plurality of different sections of an image, recording magnetically the light variations from each section separately, transmitting the recording from each image separately, erasing each recording after each transmission, and again recording as before on the erased records.

7. In a television system, the method of reproducing an image, which comprises simultaneously scanning individual points in a plurality of different portions of an image, recording simultaneously the groups of signals corresponding to each portion, reading the resulting records progressively and in succession, transmitting in succession the signals corresponding to each group, and reproducing simultaneously individual points in said different portions of the image.

8. In a television system, the method of reproducing an image, which comprises simultaneously scanning individual points in a plurality of different portions of an image, recording simultaneously, magnetically on metallic records, the groups of signals corresponding to each portion, reading the resulting records progressively and in succession, transmitting in succession the signals corresponding to each group, and reproducing simultaneously individual points in said different portions of the image.

9. In a television system, the method of reproducing an image, which comprises simultaneously scanning individual points in a plurality of different portions of an image, recording simultaneously, magnetically on metallic records, the groups of signals corresponding to each portion, reading the resulting records progressively and in succession, erasing the recorded signals from each record following the reading thereof, transmitting in succession the signals corresponding to each group, and reproducing simultaneously individual points in said different portions of the image.

10. In a television system, the method of reproducing an image, which comprises simultaneously scanning individual points in a plurality of different portions of an image, recording simultaneously, magnetically on metallic records, the groups of signals corresponding to each portion, reading the resulting records progressively and in succession, erasing the recorded signals from each record following the reading thereof, transmitting in succession the signals corresponding to each group, reproducing simultaneously individual points in said different portions of the image, and again scanning the image and recording as before the individual points in a plurality of different portions of the image on the records, the recordings of which have been erased, and continuing to read the records, transmit the signals, and reproduce the image as before.

JOHN LOGIE BAIRD.
